(57) **CLAIM**

The ornamental design for a book display module, as shown.

DESCRIPTION

FIG. 1 is a top, front and left side perspective view of a book display module showing my new design.

FIG. 2 is front elevational view thereof.

FIG. 3 is rear elevational view thereof.

FIG. 4 is right side elevational view thereof.

FIG. 5 is left side elevational view thereof.

FIG. 6 is top plan view thereof.

FIG. 7 is bottom plan view thereof.

FIG. 8 is a top, front and left side perspective view of a book display module showing an alternative embodiment of my new design.

FIG. 9 is front elevational view thereof.

FIG. 10 is rear elevational view thereof.

FIG. 11 is right side elevational view thereof.

FIG. 12 is left side elevational view thereof.

FIG. 13 is top plan view thereof; and,

FIG. 14 is bottom plan view thereof.
